US0D1073731S

(12) **United States Design Patent** (10) Patent No.: **US D1,073,731 S**
Manzoni (45) Date of Patent: ** May 6, 2025

(54) **DISPLAY SCREEN WITH GRAPHICAL USER INTERFACE**

(71) Applicant: **FERRARI S.p.A.**, Modena (IT)

(72) Inventor: **Flavio Manzoni**, Modena (IT)

(73) Assignee: **FERRARI S.p.A.**, Modena (IT)

(**) Term: **15 Years**

(21) Appl. No.: **35/519,145**

(22) Filed: **Nov. 29, 2022**

(80) **Hague Agreement Data**

Int. Filing Date: **Nov. 29, 2022**

Int. Reg. No.: **DM/225413**

Int. Reg. Date: **Nov. 29, 2022**

Int. Reg. Pub. Date: **Dec. 1, 2023**

(30) **Foreign Application Priority Data**

May 31, 2022 (WO) WIPO118134

(51) **LOC (15) Cl.** **14-04**

(52) **U.S. Cl.**

USPC **D14/486**; D14/492

(58) **Field of Classification Search**

USPC D14/485-495
